CONTROL SYSTEM

Charles P. Croco, Mount Lebanon, Pa., assignor to Westinghouse Electric Corporation, East Pittsburgh, Pa., a corporation of Pennsylvania

Application May 13, 1958, Serial No. 735,042

6 Claims. (Cl. 315—131)

This invention relates generally to control systems and, more particularly, to systems in which push-button switches are utilized for controlling the operation of electrically operated devices, such as contactors and motor starters which are located remotely from the switches. In such systems indicating lamps are usually installed on switchboards and control panels to provide an indication of the functioning of apparatus located remotely from a switchboard or control panel.

In order to save time in locating control system faults, indicating lamps are so constructed that a lamp can be tested for burn-out by pushing on the lens of the lamp thereby connecting the lamp to a test circuit. Furthermore, in order to reduce the amount of apparatus and the space required for mounting the apparatus, a combined indicating lamp and push-button switch has been devised, such as the device described in a copending application of A. J. Matiyak et al., Serial No. 649,873, filed April 1, 1957.

An object of this invention is to provide a simplified and improved control system utilizing a combined push-button switch and indicating lamp.

Another object of the invention is to provide for connecting the lamp of a combined push-button switch and indicating lamp across a power source by depressing the lamp.

A further object of the invention is to provide for utilizing a combined push-button switch and indicating lamp in conjunction with a push-button switch to perform the functions of "starting," "stopping," "indicating" and "testing" in a control system for an electrically operated device.

Other objects of the invention will be explained fully hereinafter or will be apparent to those skilled in the art.

In accordance with one embodiment of the invention, a combined indicating lamp and push-button switch is so connected in a control system in conjunction with a push-button switch that the push-button switch is depressed momentarily to energize a motor starter or contactor. The lamp is energized and the starter is held closed by means of a holding circuit established through auxiliary contact members on the starter. The lamp is depressed to interrupt the holding circuit and deenergize the starter. The lamp is also depressed to connect it across a power source to test the lamp for burn-out.

For a better understanding of the nature and objects of the invention, reference may be had to the following detailed description, taken in conjunction with the accompanying drawing in which:

Figure 1 is a diagrammatic view of a control system embodying the principal features of the invention; and

Fig. 2 is a view, partly in section and partly in elevation of a combined push-button switch and indicating lamp utilized in the control system.

Referring to the drawings, and particularly to Fig. 2, the switch shown therein may be of the type described in the aforesaid copending application. The switch comprises a supporting sleeve 10, preferably composed

2

of a cast metal, and having a flange 11 at the inner end thereof for engaging the inner side of a supporting panel 12. A sealing disc 13, preferably composed of rubber or the like, is interposed between the flange 11 and the inner surface of the panel 12. The outer end of the sleeve 10 is externally threaded for receiving a clamping ring 14 which is adapted to secure the sleeve to the panel 12 when the clamping ring is drawn down tightly. A metal washer 15 may be provided between the clamping ring 14 and the outer surface of the panel 12.

The supporting sleeve 16 is provided with a transversely extending web 16 having an opening 17 therein. A housing 18 is slidably disposed in the opening 17. The upper end of the housing 18 is enlarged and threaded internally to receive a lens 19 which may also be used as a push-button. A sealing washer 21 is provided between a shoulder 22 on the lens 19 and the top of the housing 18. A lamp receptacle 23 is disposed inside the housing 18 and a lamp bulb 24 is disposed in the receptacle 23. The bulb 24 is protected by the lens 19. The receptacle 23 is retained in the housing 18 by projections 25 which extend through an opening in the bottom of the housing 18 and also extend through an opening in an operating member 26 which is attached to the bottom of the housing 18 by riveting the projections 25 where they extend through the member 26.

A compression spring 27 surrounds the housing 18 between a shoulder 28 on the housing 18 and a metal washer 29. A sealing disc or washer 31 is provided around the housing between the metal washer 29 and the web 16 of the sleeve 10 to prevent oil or other material from passing through the opening 17. The spring 27 compresses the sealing disc 31 and biases the housing 18 outwardly. The outward movement of the housing 18 is limited by the operating member 26 which engages the bottom of the sleeve 10.

One leg of an L-shaped bracket 32 is attached to projections 33 on the bottom end of the sleeve 10 by screws 30. A terminal block 34 is attached to the bracket 32. A resistor 35 may be attached to a bracket 36. The bracket 36 may be attached to the terminal block 34. As will be described more fully hereinafter, the resistor 35 may be connected in the circuit for the lamp 24. If desired, a transformer may be utilized in place of the resistor 35 when the lamp is energized with alternating current. The lamp 24 may be connected across the line voltage in case the voltage is not higher than the rated voltage of the lamp.

An enclosed switch 37 is attached to the other leg of the bracket 32 by means of screws 38. The switch 37 is preferably of a double-throw spring-return snap-action type, such as, for example, the switch described in Patent No. 1,960,020. The switch 37 is provided with an operating plunger 39 which is engaged by the operating member 26 to actuate the switch when the lens 19 is depressed. The switch 37 is provided with contact members which control the energization of the lamp 24 as will be described more fully hereinafter.

As shown in Fig. 1, a push-button switch 41 may be utilized in conjunction with the combination indicating lamp and push-button switch shown in Fig. 2 to control the operation of a motor starter or contactor M which may be utilized to control the energization of an electric motor or other apparatus (not shown). When the push-button switch 41 is depressed, an energizing circuit is established for the actuating coil of the switch M. This circuit extends from the power conductor L1 through the contact members 42 and 43 of the switch 41 and contact members 44 and 45 of the switch 37 to the actuating coil of the switch M and thence to a power conductor L2.

When the contactor M is closed, a holding circuit for

3 the coil of the contactor is established from the power conductor L1 through auxiliary contact members Ma of the contactor and the contact members 44 and 45 of the switch 37. Thus, the switch 41 may be released after the contactor M is closed. An energizing circuit for the lamp 24 is also established at this time. This circuit extends from the power conductor L1 through the auxiliary contact members Ma, the lamp 24 and the resistor 35 to the conductor L2. Thus, the lamp is lighted to indicate that the contactor M is closed and the load is connected to the line conductors L1, L2 and L3 through main contact members M1, M2 and M3 of the contactor M.

If it is desired to disconnect the load from the line conductors, the lamp 24 is depressed to actuate the switch 37, thereby opening the circuit through its contact members 44 and 45 which interrupts the holding circuit for the coil of the contactor M. At the same time Ma opens the circuit to lamp 24, thereby extinguishing the lamp.

If it is desired to test the lamp 24 for burn-out, the lamp is depressed, thereby actuating the switch 37 to establish a circuit through contact members 46 and 47 of the switch. The lamp 24 is then connected directly across the power conductors L1 and L2 in series with the resistor 35. It will be noted that the testing circuit for the lamp 24 does not include the push-button switch 41. Accordingly, the failure of the lamp 24 to light when the testing circuit is closed indicates that the lamp is burned out.

From the foregoing description, it is apparent that the invention provides a control system which is suitable for controlling the operation of a motor starter or another electrically operated device. By utilizing the combination indicating lamp and push-button switch the amount of apparatus required is reduced. The system provides for a "push to start," "a light for run," "a push to stop" and "a push to test" operations. The testing circuit for the indicating lamp is independent of the starting push-button and the auxiliary contact members on the motor starter or contactor. Thus, a burn-out of the indicating lamp may be readily detected.

Since numerous changes may be made in the above described construction and different embodiments of the invention may be made without departing from the spirit and scope thereof, it is intended that all the matter contained in the foregoing description or shown in the accompanying drawing shall be interpreted as illustrative and not in a limiting sense.

I claim as my invention:

1. In a control system, in combination, an electrically operated device having an actuating coil, a first switch having contact members for controlling the energization of the coil, a second switch having first contact members for controlling the deenergization of the coil, second contact members on the second switch, a lamp for indicating the functioning of the device, said lamp being movable to actuate said second switch, auxiliary contact members actuated by said device for controlling the energization of the lamp, and said second contact members being actuated by moving said lamp to establish a testing circuit for the lamp independently of said auxiliary contact members.

2. In a control system, in combination, an electrically operated device having an actuating coil, a first switch having contact members for controlling the energization of the coil, a second switch having contact members for controlling the deenergization of the coil, additional contact members on the second switch, a lamp for indicating

5 the functioning of the device, said lamp being movable to actuate said second switch, auxiliary contact members actuated by said device for controlling the energization of the lamp, and said lamp being movable to establish a testing circuit for the lamp through said additional contact members independently of said auxiliary contact members.

3. In a control system, in combination, an electrically operated device having an actuating coil, a first switch having contact members for controlling the energization of the coil, a second switch having contact members for controlling the deenergization of the coil, additional contact members on the second switch, a lamp for indicating the functioning of the device, said lamp being movable to actuate said second switch, auxiliary contact members actuated by said device for controlling the energization of the lamp, and said lamp being movable to establish a testing circuit for the lamp through said additional contact members independently of said first switch and said auxiliary contact members.

4. In a control system, in combination, an electrically operated device having an actuating coil, a first switch having contact members for controlling the energization of the coil, a second switch having first contact members for controlling the deenergization of the coil, second contact members on the second switch, a lamp for indicating the functioning of the device, said lamp being movable to actuate said second switch, auxiliary contact members actuated by said device and cooperating with the first contact members on said second switch to establish a holding circuit for said device, and said second contact members being actuated by moving said lamp to establish a testing circuit for the lamp independently of the auxiliary contact members and the first switch.

5. In a control system, in combination, an electrically operated device having an actuating coil, a first switch having contact members for controlling the energization of the coil, a second switch having contact members for controlling the deenergization of the coil, a lamp for indicating the functioning of the device, said lamp being movable to actuate said second switch, auxiliary contact members actuated by said device and connected in series with contact members of said second switch to establish a holding circuit for said device, and said lamp being movable to establish a testing circuit for the lamp by actuating the second switch independently of said auxiliary contact members and said first switch.

6. In a control system, in combination, an electrically operated device having an actuating coil, a first switch having contact members for controlling the energization of the coil, a second switch having contact members for controlling the deenergization of the coil, a lamp for indicating the functioning of the device, said lamp being movable to actuate said second switch, auxiliary contact members actuated by said device to establish an energizing circuit for said lamp, said auxiliary contact members being connected in series with contact members of said second switch to establish a holding circuit for said device, and said lamp being movable to establish a testing circuit for the lamp by actuating the second switch independently of said auxiliary contact members and said first switch.
